[57] CLAIM

The ornamental design for a vehicle windshield defroster, as shown and described.

DESCRIPTION

FIG. 1 is a top perspective view of a vehicle windshield defroster, showing my new design;

FIG. 2 is a top plan view thereof;

FIG. 3 is a front elevation view thereof, the rear being a mirror image of that shown;

FIG. 4 is a bottom plan view thereof;

FIG. 5 is an end elevation view thereof, the opposite end being a mirror image of that shown;

FIG. 6 is a top perspective view of a vehicle windshield defroster showing a second embodiment of my new design;

FIG. 7 is a top plan view of FIG. 6;

FIG. 8 is a front elevation view of FIG. 6, the rear being a mirror image of that shown; and,

FIG. 9 is a bottom plan view of FIG. 6.

FIG. 1.

FIG. 2.

FIG. 3.

fig. 4.

fig. 5.

fig. 6.

FIG. 7.

FIG. 8.

FIG. 9.
